Primary Examiner — Carol P Rademaker(74) *Attorney, Agent, or Firm* — Ober, Kaler, Girmes & Shriver; Royal W. Craig(57) **CLAIM**

The new, original, and ornamental design for a bottle, as shown in FIGS. 1-7.

DESCRIPTION

FIG. 1 is a top, front, right side perspective view of the bottle according to my new design;

FIG. 2 is a bottom, back, right side perspective view thereof;

FIG. 3 is a front elevational view thereof;

FIG. 4 is a back elevational view thereof;

FIG. 5 is a right side elevational view thereof, the left side elevational view being a mirror image;

FIG. 6 is a top plan view thereof; and,

FIG. 7 is a bottom plan view thereof.

The broken lines in the drawings illustrate portions of the bottle which form no part of the claimed design.
